[57] CLAIM

The ornamental design for an electronic copying machine, substantially as shown and described.

DESCRIPTION

FIG. 1 is a front, top and right side perspective view of

an electronic copying machine showing our new design;

FIG. 2 is a front, top and left side perspective view thereof;

FIG. 3 is a front elevational view thereof;

FIG. 4 is a right side elevational view thereof;

FIG. 5 is a rear elevational view thereof;

FIG. 6 is a left side elevational view thereof;

FIG. 7 is a top plan view thereof;

FIG. 8 is a front, top, and right side perspective view of a second embodiment of our new design of FIGS. 1-7;

FIG. 9 is a front, top and left side perspective view thereof;

FIG. 10 is a front elevational view thereof;

FIG. 11 is a right side elevational view thereof;

FIG. 12 is a rear elevational view thereof;

FIG. 13 is a left side elevational view thereof;

FIG. 14 is a top plan view thereof;

FIG. 15 is a front, top, and right side perspective view of a third embodiment of our new design of FIGS. 1-7;

FIG. 16 is a front, top and left side perspective view thereof;

FIG. 17 is a front elevational view thereof;

FIG. 18 is a right side elevational view thereof;

FIG. 19 is a rear elevational view thereof;

FIG. 20 is a left side elevational view thereof;

FIG. 21 is a top plan view thereof;

FIG. 22 is a front, top, and right side perspective view of a fourth embodiment of our new design of FIGS. 1-7;

FIG. 23 is a front, top and left side perspective view thereof;

FIG. 24 is a front elevational view thereof;

FIG. 25 is a right side elevational view thereof;

FIG. 26 is a rear elevational view thereof;

FIG. 27 is a left side elevational view thereof;

FIG. 28 is a top plan view thereof;

FIG. 29 is a front, top and right side perspective view of a fifth embodiment of our new design of FIGS. 1-7;

FIG. 30 is a front, top and left side perspective view thereof;

FIG. 31 is a front elevational view thereof;

FIG. 32 is a right side elevational view thereof;

FIG. 33 is a rear elevational view thereof;

FIG. 34 is a left side elevational view thereof; and

FIG. 35 is a top plan view thereof.
